WARP STOP MOTION FOR LOOMS

Application filed March 21, 1929, Serial No. 437,813, and in Switzerland March 22, 1929.

Warp stop motions for looms are known, in which toothed bars with oppositely directed teeth extend through the heddle frame ends, the displacement of which with respect to one another is prevented by the dropping of a heddle, on a warp thread breaking, the loom being stopped thereby. These warp stop motions, however, had devices for moving the stop motion bars and initiating the stopping of the loom, which on account of their complicated and inaccessible construction were of no practical use.

This invention relates to a warp stop motion of the above kind, which has a very simple, easily and practically manipulated device for moving the bar and initiating the stopping of the loom. This device is characterized in this, that the displaceable toothed bar is guided in the longitudinal slot of a rail fixed to the heddle frame and that a bell crank pivoted on the heddle frame is connected at one end with the movable bar and at the other end with a pull wire which, when the loom is operating normally, allows the bar to move, but, on a warp thread breaking and the bar being locked, causes the stopping of the loom to be initiated.

The accompanying drawings illustrate various constructional examples of the invention.

Figs. 1, 2 and 3 are three elevations of the first example showing the parts in different positions. Fig. 4 is a side elevation showing the heddle frames and heddles in different positions. Fig. 5 is a side elevation of a modification having equally marking heddle frames necessitating only a common hook and wire. Figs. 6 and 7 show portions of the toothed bars in elevation.

Figs. 8, 9 and 13 show a second example with the parts in different positions.

Figs. 10 and 14 show diagrammatically different positions of the crank shaft.

Figs. 11 and 12 show a rocking push member in side elevation and in plan view with a roller in stationary bearings on the front part of the machine frame.

Fig. 15 shows the push member in another position to that of Fig. 12.

Figs. 16 and 17 show an untoothed, oval,

heddle carrying bar and two bars having similar but oppositely directed teeth in the lowered and raised positions.

Figs. 18 and 19 show a heddle resting on the untoothed, oval, bar and the same lowered and engaged by a toothed bar.

Fig. 20 shows the untoothed, oval, bar and levers for raising and lowering the toothed bars.

Fig. 21 shows an eight-end sateen weave.

Figs. 22, 23 and 24 show harness bars with two or three rows of heddles and a common bell crank for actuating the bars.

1 and 1¹ (Figs. 1 to 3, 4 and 5) are the usual heddle frames and 2, 2¹ and 2² the usual heddles. The warp threads in the upper shed are marked 4 and those in the lower shed are marked 5 (Fig. 4). By being in tension they keep the heddles raised. The latter rest through the tension of the warp threads after the commencement of the motion to form the upper shed on two horizontal bars 6 and 7 with oppositely directed teeth (Figs. 6 and 7). The bar 6 is horizontally slidable in the bar 7 of U-shaped cross-section and has a transverse pin 8 which extends through two horizontal slots 9 in the bar 7 which is fixed immovably in the heddle frame. One arm of a bell crank 10 which is pivoted on the heddle frame 1 or 1¹ engages round the pin 8 with its forked end, while to the other arm of the bell crank 10 is attached a vertical wire 12 the upper end of which is bent over to form a hook 11. Adjacent to the wire 12 is suspended a stationary wire 13, the lower end of which is bent over. A helical spring 14 embraces the two wires 12 and 13 having its lower end resting against the bent over portion of the wire 13 and its upper end free. The function of the hook 11 on the wire 12 is to press on a latch 15 which acts through the rod 16 so as to stop the loom when the shed is open.

The warp stop motion described above operates as follows:

When the heddle frame 1 (Fig. 1) is in its top position the bell crank 10 will have been turned to the left by the helical spring 14, which is only pressed together by the heddle frame moving out of the middle position into

100

the bottom position and by the weight of the wire 12 and the toothed bar 6 will have been displaced to the left before the heddle frame has passed into the upper shed, as the heddles 2 rest on the toothed staves 6 and 7 through the tension in the warp threads 4 after the commencement of the motion for forming the upper shed. The stationary wire 13 together with the helical spring 14 and the pull wire 12 oppose the motion of the heddle frame for forming the lower shed, causing the bell crank 10 and the bar 6 to be moved to the right (see Fig. 2), the heddle frame 1¹ being in its lowest position. As the heddles 2¹ of the heddle frame 1¹ are raised by the warp threads 5 of the lower shed the displacement of the bar 6 can take place unhindered.

Fig. 3 shows the heddle frame 1¹ also in its lowest position. On a warp thread 17 of the lower shed breaking the corresponding heddle 2² is no longer held up and drops into the teeth of the bars 6 and 7, thereby preventing the bell crank 10 and the bar 6 moving into the extreme right hand position. Consequently the pull rod 12 will be drawn down further to a corresponding extent, the latch 15 which rocks about a fixed pin 18 is lowered and the stopping of the loom is initiated with the shed open. In Fig. 4 the heddle frames 1, 1¹ and the heddles 2, 2¹, 2² are shown in the positions corresponding to Figs. 1, 2 and 3. Fig. 5 shows the similarly operating heddle frames 1 and 1¹ controlled by common pull wires 12 and 13.

The above described constructional form of warp stop motion in the harness is intended for fabrics in which half the heddle frames change regularly from the top position into the bottom position. The horizontally displaceable toothed bar, the oppositely toothed stationary guiding bar and the bell crank for displacing the former bar are disposed below the warp.

The constructional form of the warp stop motion illustrated in Figs. 8-15 enables it to be generally employed for fabrics in which individual groups of heddle frames remain for an unlimited period in the lower shed and only alternately single heddle frames or several heddle frames remain in the upper shed during one or more picks, all the leaves remaining in the lower shed being controlled for broken warp threads during each pick. For effecting this according to the invention the rodwork for the horizontal displacement of the bar is actuated independently of the heddle frame motion, the heddles rest at the moment of working in the upper shed on a smooth untoothed bar, two oppositely toothed bars guided in an untoothed bar can be raised and lowered by a relative displacement and the toothed bars and the levers serving for their displacement are arranged above the warp.

1 (Fig. 8) is the top motion harness, 2 are the heddles acting on the warp threads 4, 3 is a toothed guiding bar which for making it more readily accessible and for preventing it as far as possible from becoming filled with dust is arranged not below the warp, as in the first example, but above the warp rigidly in the harness, the said guiding bar being of oval cross-section for enabling the heddles resting on it to be moved easily. In a longitudinal slot in the guiding bar 3 the toothed bar 6' having oppositely directed teeth to the bar 3 is longitudinally displaceable. By means of the bell crank 10 one arm of which is subjected to the pull of a spring 10¹ and so acted on by the pull rod 12 and which is also disposed above the warp, the bar 6' can be slid in the stationary bar 3. The upper end of the pull rod 12 extends through a two-armed lever 30 having a fixed pivot and supports a vertically adjustable follower 31. The lever 30 is actuated by a pull rod 32, a bell crank 34 to which a tension spring 33 is attached and a continuously rotating cam 35. Fig. 8 shows the harness at the moment in which it has reached its lowest position, the adjustable follower 31 being exactly above the lever 30. This position corresponds to the angular position 100 (Fig. 10) of the crank shaft. Fig. 9 shows the parts in the angular position 101 of the crank shaft (Fig. 10). The horizontal arm of the bell crank 34 is lowered and the toothed bar 6' has been pushed to the right by the parts 32, 30, 31, 12 and 10.

A second bell crank 36 has one arm acted on by a tension spring 37 and actuated by the cam 38. To the horizontal arm of the bell crank 36 a vertical rod 39 is pivotally attached (Figs. 8, 9, 11, 12, 13 and 15), which operates a carrier 40 and in the latter a rocking two-armed push member or repeller 41. The rod 39 extends through a lever 42 which acts on the stop mechanism. When the rod 39 is in its lowered position the push member or repeller 41 occupies a position (Fig. 13) in which during the forward motion of the slay 43 (Fig. 13) it is struck by a striking member 44 fixed to the slay and can thereby rock the lever 42 for stopping the loom.

A stationary roller 46 supported on the front portion of the machine frame 45 is intended to rock the push member or repeller 41 out of the path of the thrust piece 44 after the repeller has initiated the stoppage of the loom and before the end of the oscillation of the slay towards the breast beam to make provision for the necessary but short movement of the slay that takes place during the actual stopping of the loom and to enable the slay to complete its forward movement when the loom is restarted. The length of the roller 46 is equal to the amplitude of movement of the rod 39 so that the front arm of the repeller 41 in both its upper and lower positions bears against the roller. On the

rocking arm 40 is rotatably supported a two-armed pawl 47, one arm of which is subject to the pressure of a spring 48, whilst the other arm is intended to hold the head 50 of the rod 39, which is adapted to be depressed by hand, for any desired period in order to disconnect the stopping device, the repeller 41 occupying the position shown in dot-and-dash lines in Figure 11. A rod 51 (Figures 8 and 13) resiliently connects the lever 30 with a bell-crank lever 52 having a stepped vertical arm, by means of which the bell-crank lever 36 can be locked in its lower position.

Normally, however, the rod 39 is caused to perform upward and downward movements through the agency of the cam 38. This movement can be interrupted so that the rod 39 remains at a half-way or middle position whereby the thrust piece 44 is directed on to the repeller 41, this being effected when the lever 36 is locked by the bell-crank lever 52. The lever 36 is again influenced by the rod 32 and the lever 30 when a heddle 2¹ is gripped in the serrations of the rods 3 and 6¹, so that the bell-crank lever 10 and the tension wire 12 remain in a half-way position.

In Figure 13 it is assumed that the heddle 2¹ is lowered in consequence of breakage of the warp thread 4¹, and the displaceable stop motion bar 6¹ therefore locked by the dropped heddle 2¹. The lever 34 is lowered by the cam 35 but the rod 32 operated through a spring S is hindered in its movement, since the positioning follower 31 is held down by the wire 12 and the bell-crank lever 10 by the engagement of the lowered heddle in bars 3 and 6¹ and by the interruption of the displacement thereof. The lever 30 and rod 51 are thereby retained in the middle position shown in Figure 13 and the bell-crank lever 52 remains in a position in which it locks the bell-crank lever 36 so that it cannot be raised by the pull of the spring 37. Consequently the rod 39 remains in the middle position in which the rotatable repeller 41 is engaged and pushed back by the thrust piece 44, whereby the loom is stopped. Normally when the heddle 2¹ is not lowered, the rod 32, the lever 30 and the rod 51 are lowered, the lever 52 is operated by the rod 51 and is moved out of its locking position, thus causing the lever 36 to be raised by its spring 37 and to raise the rod 39 to a position where the repeller 41 is above the level of the part 44.

In Figure 14, 101 again denotes the angular position with the maximum displacement of the toothed bar 6¹ the angular position 102, the moment of commencement of the stoppage of the loom by the thrust piece 44 and the repeller 41, and 103 the angular position at which the loom has already come to a standstill. This occurs 15 millimeters before the throw of the reed on the material.

The stopping of the slay about 15 m/ms. be-

fore the throw of the reed on the material is effected by a brake, preferably a band brake, which is brought into action to stop the loom earlier than is usually the case through the action of the thrust piece 44 on the repeller 41. The actuating contact between the repeller and the thrust piece for initiating the stoppage of the loom takes place about 5 cms. before the foremost position of the slay, as a result of which it is necessary for the repeller 41 to be subsequently deflected by the roller 46 from the path of the thrust piece 44 in order to enable the slay to continue its forward movement unhindered (Fig. 15) whilst the loom is stopping, the actual stoppage occurring at a predetermined distance from the forwardmost position of the slay and previous to the beat up, this predetermined distance varying with the point at which the thrust piece 44 is arranged to first contact with the repeller 41.

As a result it is possible to stop the loom about 15 m/ms. before the foremost position of the slay.

Accordingly the loom does not have to be rotated back for the purpose of drawing in broken warp threads.

The disconnection of the automatic stop motion by means of pressure on the knob 50 of the rod 39 and the consequent lowering of the repeller 41 under the thrust piece 44 is to enable it to be interrupted at will, in the event of irregularities in the warp tension, warp threads running out, and so forth, until the disturbing warp threads are found. By the method hereinbefore described of actuating the rodding for the horizontal displacement of the stop motion bar 6¹ independently of the motion of the leaf of heddles a general application of the warp stop motion harness is rendered possible, that is to say, for two-shaft and multi-shaft fabrics in which individual groups of leaves of heddles remain in the lower shed for any desired time, all the leaves that remain in the lower position being controlled as regards warp-thread breakage during every pick.

When a heddle frame is raised the corresponding follower 31 is raised away from the lever 30 so that it cannot interfere with or be affected by the movements thereof. Consequently the corresponding bar 6¹ remains stationary whilst the heddle frame is in its raised position.

In the example shown in Figs. 16-20 the stationary toothed bar 3 (Fig. 8) is replaced by an untoothed guiding bar 3¹ which is fixed to the harness, two bars 6² and 7² having similar but oppositely directed teeth being capable of sliding with respect to one another in a longitudinal groove in the bar 3¹. The bars 6² and 7² are lowered at the moment when the heddle frames are working in the upper shed into the untoothed guiding stave 3¹ so that the heddles 2 rest on the smooth

bar 3¹ and conversely are raised out of the bar 3¹ at the moment in which the heddle frames are in their bottom position, for engaging with any heddles that may have dropped through the breakage of warp threads.

The following arrangement is provided for operating the stop motion bars 6² and 7²: The pull rod 12 (Fig. 20) is connected to 10 two bell cranks 10² and 10³ which are pivoted to the stop motion harness and each of which is provided with a forked arm. On the leaf bars 6² is fixed a pin 54 which extends through an inclined slot 53 in the bar 15 3¹ of oval cross-section, and on the bar 7² a pin 56 which extends through an oppositely inclined slot 55 in the bar 3¹. The pin 54 is engaged by the forked arm of the bell crank 10² and the pin 56 by that of the bell 20 crank 10³. Figs. 16 and 18 show the two toothed bars 6² and 7² in the position in which they have been lowered into the bar 3¹ by the members 51, 10², 10³, 53—56 so that the heddles 2 rest on the bar 3¹. Fig. 20 shows 25 the bars 6² and 7² raised out of the bar 3¹ by the inclined slots 53 and 55 and the pins 54 and 56 and ready for feeling for any heddles dropped by the breaking of a thread. Fig. 19 shows a dropped heddle 2 which has been 30 engaged by the toothed bars 6², 7² and therefore prevents their further displacement and stops the loom. In the 8-end sateen weave shown in Fig. 21 the heddle frame 1 remains in the lower shed for 7 picks, during which 35 period the bars check seven times whether any warp threads are broken.

Figs. 22, 23 and 24 show heddle frames 1¹ with two and three fixed toothed bars 7³ lying one behind the other, bars 6³ which are slidable in the same and two or three rows of 40 heddles 2. A common bell crank 10⁴ actuates the two or three bars 6 lying one behind the other by engaging with the transverse pin 8 common to them all.

45 What I claim is:

1. In a warp stop motion for looms, the combination with a heddle frame provided with a series of heddles, a stationary toothed bar supported by the heddle frame, a counter-toothed bar longitudinally movable in the said frame, both toothed bars being movable together with the heddle frame, means for longitudinally moving the second toothed bar independently of the motion of the heddle frame, a push member pivotally mounted on a vertically movable rod controlled by the movable toothed bar and capable of operating the stopping device, a striking member fixed to the slay and capable of acting upon the lower push member and a roller mounted in the front part of the machine and capable of rocking the said push member out of the path of the striking member before the slay has completed its forward swinging movement.

2. In a warp stop motion for looms, the combination with a heddle frame provided with a series of heddles, a stationary toothed bar supported by the heddle frame, a counter-toothed bar longitudinally movable in the 70 said frame, both toothed bars being movable together with the heddle frame, means for longitudinally moving the second toothed bar independently of the motion of the heddle frame, a push member pivotally mounted on a vertically movable rod controlled by the 75 movable toothed bar and capable of operating the stopping device, means to manually lower the said rod to bring the said push member out of the path of the striking member of the slay and means to lock the said rod in the lowered position to render the stop motion inoperative or to be interrupted at will.

In testimony whereof I have affixed my 85 signature.

ERNST EGLI.
